GRAB RAIL FOR SWIMMING POOLS

Jack A. Berg, Van Nuys, Calif., assignor to Marine Swimming Pool Equipment Company, North Hollywood, Calif., a corporation of California

Filed July 19, 1965, Ser. No. 86,210

Term of patent 14 years

(Cl. D13—1)

FIG. 1 is an outer side elevational view of a grab rail embodying the design;

FIG. 2 is a plan view of the same;

FIG. 3 is an inner side elevational view of the same;

FIG. 4 is a rear elevational view of the same; and

FIG. 5 is a front elevational view of the same.

I claim:

The ornamental design for a grab rail for swimming pools, as shown.
